UNITED STATES PATENT OFFICE.

FRANK BOTTOMLY, OF WORCESTER, MASSACHUSETTS, ASSIGNOR TO JOHN H. COES AND FREDERICK L. COES, OF WORCESTER, MASSACHUSETTS.

WRENCH.

SPECIFICATION forming part of Letters Patent No. 690,047, dated December 31, 1901.

Application filed October 29, 1901. Serial No. 80,426. (No model.)

To all whom it may concern:

Be it known that I, FRANK BOTTOMLY, a citizen of the United States, residing at Worcester, in the county of Worcester and State of 5 Massachusetts, have invented a new and useful Improvement in Wrenches, of which the following, together with the accompanying drawings, is a specification sufficiently full, clear, and exact to enable persons skilled in 10 the art to which this invention appertains to make and use the same.

The present invention, which relates more especially to that class of wrenches known as the "Coes" adjustable screw-wrench, has for 15 its object to provide, in combination with the several parts of the wrench, a simple and efficient means for retaining the adjusting-screw journal or bearing end in proper relation to the bearing-step of the collar or handle-frame 20 ferrule without requiring the notching of the wrench-bar for engagement with the rosette-head of the adjusting-screw. I attain such object by the mechanism illustrated in the accompanying drawings, wherein—

25 Figure 1 represents a side view of a wrench embodying my invention. Fig. 2 is a vertical section at the junction of the adjusting-screw and collar. Fig. 3 is a plan view of the top end of the collar or handle-frame. 30 Fig. 4 represents the yoke or retaining plate separately in detail by side and plan views, and Fig. 5 shows a side view of the rosette and bearing end of the screw.

Referring to the drawings, A indicates the 35 wrench-bar, having the fixed jaw or head *a* and formed with handle-positioning shoulders 2, but without a rosette recess or notch at the front of the bar.

B indicates the sliding jaw, of well-known 40 form; C, the adjusting-screw, provided with the usual thumb-boss or rosette C', and D indicates the bearing-collar or upper end of the handle-frame, fitting the neck *a'* of the bar-shank and carrying the handle-plates E in 45 suitable manner. According to my present invention the bearing end or journal of the screw C is formed with a circumferential groove 3 adjacent to the rosette C' and a flange 4 below, as best shown in Figs. 2 and 5. The 50 step projection *d* of the collar has its bearing-

opening 6 made of a size to correspond with and receive the flange 4 or end of the adjusting-screw journal. For retaining the screw in proper relation I provide a supplementary collar, yoke, or interlock plate F, Fig. 4. 55 Said plate F is preferably made of flat steel about one-eighth of an inch, more or less, in thickness. The external outline is shaped substantially the same as the end of the collar D. Through the collar-plate I form an 60 opening 7, corresponding to the cross-section of the neck *a'* of the wrench-bar A, and from said opening I form a forwardly-extending slot 8 with a semicircular end 5, said slot corresponding in width to the diameter of the 65 grooved portion 3 of the screw-journal. The circle at the end 5 is made axially coincident with the bearing-cavity 6 in the projecting step *d*. The thickness of the plate F and groove 3 approximately correspond, so that 70 the plate will interlock into said groove, affording an easy running fit.

When the parts are assembled, the end 4 of the adjusting-screw journal is passed through the opening 7 in the plate F and the 75 grooved part 3 slipped into the slot 8, so that the semicircular end 5 locks into said groove 3. The jaw B, with the end of the screw C entered therein, is then slipped onto the bar A, together with the plate F, the latter stopping against the positioning-shoulders 2. The handle-frame is then driven onto the bar-shank in usual manner, the cavity 6 fitting over the end 4 of the journal and the top end 80 of the collar fitting firmly and flat against the 85 under side of the plate F, which latter is thereby rigidly held between the said collar end and the shoulders 2 on the bar when the handle is secured to the bar-shank in well-known manner by the tip-piece G and a transverse pin I or by other efficient means. The 90 adjusting-screw C is freely rotatable in its bearing, but is confined from endwise displacement by the engagement of the plate in the groove 3 and from lateral displacement 95 by engagement of the flanges 4 in the cavity 6. The screw is thus secured in proper relation, as shown in Figs. 1 and 2.

By the plate F a very simple and efficient means of attachment is provided, as such 100

plate can be readily made by drop-forging or punching from sheet-steel, and the assemblage of the parts can be easily and quickly accomplished.

5 What I claim, and desire to secure by Letters Patent, is—

1. In a wrench, the combination with the wrench-bar and the rosetted adjusting-screw, of a yoke or supplementary collar-plate detachable from the collar and adapted for embracing the wrench-bar and for retaining the rosette-screw from endwise displacement, substantially as set forth.

2. In a wrench of the character described, 15 a screw-retaining plate having an opening adapted to fit the neck of the bar, and a slot extending therefrom for receiving the grooved adjusting-screw journal, said plate disposed at the end of the handle frame or collar against 20 the handle-positioning shoulders; in combination with the wrench-bar, the collar, and

the jaw-adjusting screw having the grooved and flanged journal, for the purpose set forth.

3. A wrench comprising a wrench-bar having a fixed jaw, a movable jaw sliding on said wrench-bar, a handle secured to the bar-shank and having a collar carrying a projection with a circular bearing-cavity therein, a jaw-adjusting screw having a rosette and provided with a groove around its journal adjacent to the rosette, a slotted detachable collar-plate embracing the neck of bar and the journal, and interlocking with said groove, said plate confined between the end face of the handle-collar and positioning-shoulders formed on 35 said wrench-bar, substantially as set forth.

Witness my hand this 26th day of October, 1901.

FRANK BOTTOMLY.
